DECORATIVE BAR PIN

Joseph I. Levyn, Brooklyn, N. Y., assignor to Jilko Service Products, New York, N. Y., a copartnership

Application June 19, 1944, Serial No. 540,992

9 Claims. (Cl. 40—1.5)

1

My present invention relates to bar pins for personal wear, such as service bars employed to display campaign ribbons and the like, and is directed more particularly to an improved article of the type covered in my copending application Ser. No. 535,836, filed May 16, 1944.

The construction disclosed in my prior application involves readily assembleable cooperating plate members confining the ends of ribbons or other insignia between them whereby the ribbons are held in a taut, smooth condition. The construction, although well adapted for its intended purposes, requires a complete assembly for each combination of ribbons. The present invention has for its principal object the provision of a bar pin of the type referred to, comprising individual pre-assembled, ribbon-carrying elements for mounting on a supporting or backing member. The construction contemplates the provision of a backing or supporting member made in a number of lengths, for example, three lengths, to carry one, two, or three ribbons and separate self-contained holders for each individual ribbon, the holders being arranged to be mounted in any desired combination on the backing member.

Another object of the invention is the provision of an improved construction permitting ribbon-holding members to be easily assembled on a backing and supporting member, the latter carrying means for attachment to the clothing of the wearer. In a preferred embodiment of the invention, the attaching means cooperates with an element of a ribbon-holding member for securing the pin to the clothing of the wearer.

A further object of the invention is the provision of a bar pin which can be more readily and economically manufactured than prior types, and which is better adapted to serve its intended function.

My invention will be more fully understood, and further objects and advantages thereof become apparent, when reference is made to the more detailed description thereof which is to follow and to the accompanying drawings, in which:

Fig. 1 is an exploded perspective view of one form of bar pin embodying the instant invention;

Fig. 2 is a plan view of a partially assembled bar pin;

Fig. 3 is a view similar to Fig. 2, showing the bar pin after assembly has been completed;

Fig. 4 is a sectional view on an enlarged scale taken on the line 4—4 of Fig. 3;

Fig. 5 is a sectional view taken on the line 5—5 of Fig. 3;

2

Fig. 6 is a side elevational view of the device of Figs. 1—5, illustrating a feature thereof;

Fig. 7 is a plan view of a bar pin element embodying a modified form of fastening means;

Fig. 8 is a sectional view taken on the line 8—8 of Fig. 7;

Fig. 9 is a sectional view on an enlarged scale taken on the line 9—9 of Fig. 7;

Fig. 10 is an exploded perspective view, similar to Fig. 1, of a modified form of the invention;

Fig. 11 is a sectional view taken on the line 11—11 of Fig. 10, illustrating a detail of the construction;

Fig. 12 is a top plan view of the base member 15 of a bar pin construction as illustrated in Fig. 10, to be employed for a single ribbon;

Fig. 13 is a top plan view of the inlay of a ribbon holder for assembly with the base of Fig. 12;

Fig. 14 is a view similar to Fig. 12, but depicting 20 a base member to be employed in a two-ribbon pin;

Fig. 15 is a sectional view taken on the line 15—15 of Fig. 14;

Fig. 16 is a top plan view of inlays of two-ribbon holders for assembly with the base member 25 of Figs. 14 and 15;

Fig. 17 is a top plan view illustrating a partially assembled pin of the construction of Fig. 10;

Fig. 18 is an enlarged cross-sectional view 30 illustrating a modification of the construction of Figs. 10—17;

Fig. 19 is a perspective view of a keeper member employed in the modification of Fig. 18;

Fig. 20 is a top plan view of the base member 35 of the assembly disclosed in Fig. 18;

Fig. 21 is a top plan view of the ribbon-holding inlays of the assembly of Fig. 18, for use with the base of Fig. 20;

Fig. 22 is a top plan view of an element of 40 similar type to that shown in Figs. 14 and 15, but having a modified form of fastening pin;

Fig. 23 is a sectional view taken on a line 23—23 of Fig. 22;

Fig. 24 is a sectional view similar to Fig. 18, 45 illustrating a minor modification of the embodiment of Fig. 18;

Fig. 25 is a fragmentary plan view, similar to Fig. 17, but illustrating a slight modification of the base member;

Fig. 26 is an end view of the base member of Fig. 25; and

Fig. 27 is a sectional view, similar to Fig. 4, 50 showing a slight modification of the ribbon-holding unit.

Referring now to the drawings, my invention is disclosed in a number of embodiments, all of which include a common feature, namely, the provision of a base or supporting member which carries the fastening means, and individual ribbon holders adapted for ready assembly with the base or supporting member. The holders and members in each of the several embodiments disclosed are preferably made of light-gauge sheet steel, although aluminum or other non-corrosive metals may be employed. The base member is made in a plurality of sizes, suitably three sizes, to accommodate one, two, or three of the individual ribbon-holding units. As will be readily understood, any combination of three ribbons can be carried by the three-ribbon backing member, and similarly any two ribbons may be carried by the two-ribbon backing member, whereby a purchaser's requirements can be met with a minimum stock on hand. Thus, if the supplier carries a stock of assembled ribbon units representing the various military campaigns, decorations, and the like, and a supply of the backing members in the three or more sizes, campaign bars can be assembled in any desired combination to meet the requirements of different service men.

In the embodiment illustrated in Figs. 1-6 inclusive, the bar pin comprises individual ribbon holders 10 and a base and supporting member 12. A two-ribbon bar pin is shown, but it will be appreciated that base member 12 will also be made in lengths to accommodate one or three or more ribbon holders 10. The ribbon holders 10 each include an outer shell 14, an inner plate or inlay 16, and a facing material or ribbon 18. The latter may comprise a campaign ribbon or the like, or any other insignia-bearing or ornamental flexible material. The outer shell 14 is provided with side flanges 20 for a purpose to be described. Inner plate 16 is of a size to fit loosely between the flanges 20 of plate 14 and is provided with a struck-up detent 22 for a purpose to be described. Both plates 14 and 16 include elongated slots 24 and 26 respectively to permit insignia of various types to be secured on the outer face of the bar pin, such insignia including stems which are passed through the aligned slots and bent over or threaded into nuts, or otherwise secured in position.

In assembling the individual ribbon-holding units 10, the facing material 18, such as a campaign ribbon, is laid to overlie the front face of the outer plate 14, with the ends extending over flanges 20 and onto the rear face of the outer plate. Inner plate 16 is then inserted between the flanges 20 to overlie the rear face of plate 14 and to confine the ends of the facing material between the contiguous faces of the plates. Flanges 20 are then bent or crimped to approximately the extent shown particularly in Fig. 4 to lock the plates in relatively immovable relationship to one another, with the facing material securely held in place. As will be noted from an inspection of this figure, the flanges extend rearwardly from the outer plate in converging planes, with free edges spaced substantially from the inner plate, whereby the facing material is confined between the flanges and the edges of the inner plate, and at the same time the projecting flanges serve as a reinforcing means to greatly strengthen the assembly against bending. In addition, the inwardly converging flanges define a channel substantially dovetail in cross section to receive the base or supporting member 12 in endwise sliding, frictional engagement. If de-

sired, the assembled holders may be additionally crimped as indicated at 27 to ensure that the plates will not shift. The individual ribbon holders may be made up to carry the various different ribbons or insignia and stocked for later assembly in any desired arrangement with the backing and supporting plate as previously pointed out.

The base or supporting member 12 in the embodiment of Figs. 1-6 comprises a flat plate of a width to fit with sliding friction between the over-turned flanges 20 of the ribbon holders (see Fig. 4). The base 12 includes struck-up wings 28, provided with inwardly projecting protuberances 30, preferably formed by indenting the wings. The wings are formed on their forward edges with extensions 32, which may be drawn together when the wings are assembled on the pin, the projections thus forming a fulcrum or rest to tension the pin outwardly when it is moved to its locking position (see Fig. 5). Adjacent the opposite end of the base 12 is a keeper or latch 32 formed in part from a struck-up section of the member as illustrated. This end of member 12 is preferably bent downwardly to form flange 33. A pin 34 formed with an eye 36 and a pointed end 38 is mounted on base 12 by pressing the wings 28 together with eye 36 confined therebetween until protuberances 30 substantially contact within the eye to define a pintle on which the pin may rotate. Elongated slots 40 are provided in backing member 12 for alignment with slots 24 and 26 in plates 14 and 16, the right hand ends of the slots (see Fig. 3) substantially coinciding with detent 22 in plate 16 to further secure the parts against disassembly.

To assemble a campaign bar of the type described above, the selected, previously prepared ribbon-holding units are slid lengthwise onto a backing member 12 of the correct length from the right hand end (as viewed in Fig. 1), as shown in Fig. 2, until the forward ribbon-holding unit is stopped by flange 33 and the holders are in endwise contiguous relationship. The bar is then ready for attachment to the clothing of the wearer. As shown in Fig. 3, detents 22 enter slots 40 and, in conjunction with the frictional fit of the backing member between the ribbon-covered flanges 20, prevent the ribbon units from accidentally sliding off the backing plate.

Fig. 6 illustrates the adaptability of the bar pin constructed as described above for adjustment to meet the requirements of the wearer. Thus the pin may be readily bent at the joints between the individual ribbon units to give it, in effect, a curved contour whereby it will lie flat against the clothing.

Referring now to Figs. 7, 8, and 9, a construction employing a modified form of the backing and supporting member is disclosed, the ribbon holders being of the type previously described. In this form of the invention (see particularly Fig. 9), backing plate 44 is of a width to overlie the flanges of the ribbon holders and includes curved side flanges 46 embracing the ribbon units. The ribbon units are suitably somewhat modified from the form previously described to the extent that the flanges of the outer member are bent downward to a greater extent than in the other forms to obtain a rounded edge for frictional engagement with curved side flanges 46. In this embodiment ribbon units 10 are inserted endwise into the channel defined by flanges 46. The fastening means comprises a wire-like member 48 having outer projecting, pointed ends 50. Member 48 includes a circular, preferably inte-

gral eye 52 to receive a pin 54. A detachable keeper member 56 is provided comprising an elongated plate including bosses 58 to overlie pointed ends 50 and a central lock 60 having upstruck members 62 adapted to bite into pin 54 when mounted thereon and to resist removal forces, but removable from the pin when sufficient force is applied, as by means of a tool. In the use of the pin, keeper member 56 is removed and the bar placed in position on the outer surface of the clothing, with pointed ends 50 and pin 54 projecting through the clothing. Keeper member 56 is then forced down on pin 54 to firmly lock the bar in position with bosses 58 overlying sharpened ends 50 of wire 48.

Referring now to Figs. 10 to 17 inclusive, a modified form of the construction is shown, this modification being preferred in many instances. As in the constructions previously described, the bar pin includes individual ribbon holders 63 and a base or supporting plate 64. The ribbon holders consist of a ribbon or other insignia 65, an outer shell 66 of similar construction to shell 20 and formed with side flanges 68, and an inner plate or inlay 70 somewhat modified from that shown at 16. Inlay plate 70 is provided with a cut-out tongue 72 having a central aperture 74, the tongue being adapted to be struck up from the material of the plate to assume a substantially vertical position, although normally lying in the plane of the plate, both positions being shown in Fig. 10. Plates 66 and 70 include elongated slots 76 and 78 respectively for similar purposes as slots 24 and 26 in the previous embodiment.

The base or supporting member in this embodiment of the invention will take different forms, depending on whether it is to support one, two, or three or more ribbon bars. Fig. 10 discloses the construction for a three-ribbon bar, base 64 in this instance comprising an end or tongue 82 of reduced width and of a length to be positioned between the inwardly extending edges of side flanges 68 of a plate 66, with a bent-up tongue or keeper 72 of a plate 70 projecting therethrough as illustrated in Fig. 17. As shown, the reduced width of tongue 82 may be provided by cutting away the material of the member.

The portion of the member which forms the tongue may be bowed upwardly to provide the required reduction in width, but without the necessity of removing material, as shown at 83 in Figs. 25 and 26. The base 64 carries a fastener pin 84 rotatively supported on an integral hinge 86, preferably of similar construction to that shown in the embodiment of Figs. 1-5. A guide member 88 is also upstruck from member 64, the guide including a notch 90 to receive pin 84 adjacent the sharpened end thereof (see Figs. 10 and 11). The end of member 64 opposite tongue 82 carries an integral flange or stop 92. Elongated slots 94 and 95 are formed in the base member, slot 94 which extends into tongue 82, being of a width to receive keeper 72 of plate 70.

In the assembly of a three-ribbon bar, two of the individual ribbon units, constructed as previously described are inserted on the tongued end of base member 64 and slid therewith until the forward holder reaches stop 92. Both of these holders have their tongues 72 in their original flattened positions within the plane of the plate. The tongue 72 of the third holder is retained in its outwardly projecting position to constitute a keeper for the fastening pin (see Figs. 10 and 17). The third unit is then applied to the base mem-

ber by inserting keeper 72 through slot 84, with tongue 82 of member 84 interfitting between flanges 68. The bar pin is then ready to be worn. In attaching the bar, pin 84 is caused to penetrate the clothes of the wearer, and the third ribbon-holding unit, as shown at the left-hand end in Fig. 17, is moved to the right until it lies in endwise contiguous relationship to the previously applied unit, the end of pin 84 entering perforation 74 in keeper 72 during such endwise movement. Notched guide 88 aligns pin 84 with perforation 74 to ensure entry of the pin into the perforation. Where the bowed end 83 of Figs. 25 and 26 is employed, the bowed end is preferably flattened after the three ribbon units are assembled on the base to prevent complete separation of the parts thereafter.

As indicated at 96 (see Fig. 17), the outer ends of the flanges of the third ribbon holder may be further bent or crimped downwardly to ensure frictional contact with tongue 82 to assist in preventing accidental endwise shifting of the holder.

Referring now to Figs. 12 and 13, a construction for a single-ribbon bar is illustrated. The ribbon-holding units are the same as before. A base member 98 is provided of a similar construction to member 64 except that, in addition to its reduction in length to accommodate a single ribbon holder, it is made of the same width throughout and an open-ended slot 100 is provided, terminating in an upstruck guide 102 of similar form to guide 88. The central slot 99 in this form is broken, leaving a short strip or bridge of metal 101 adjacent the outward end of the slot, for a purpose to be described.

In making the assembly of the one-ribbon bar pin, the unit carrying the ribbon, which is of identical form to that employed for the three-ribbon pin of Fig. 10, but reversed end for end as indicated in Fig. 13, is inserted endwise over the notched end of base member 98. The pin is then caused to penetrate the clothing and its free end is supported in notched guide 102. The ribbon holder is then further slid on base 98, with the pin entering the perforation in the keeper 72 of the ribbon unit, the sliding motion continuing until the keeper 72 reaches the end of the slot 100. After the ribbon unit has been partially mounted on the base plate 98, the strip or bridge 101 is pressed downwardly into the slot in the underlying inlay 70, thereby preventing complete separation of the ribbon unit from the base plate.

Figs. 14, 15, and 16 disclose a construction for a two-ribbon bar pin. The ribbon-holding units as shown in Fig. 16 are identical with those employed in the construction of Figs. 10 and 13. Base member 104 (see Figs. 14 and 15) is essentially the same as base member 98, except that it is of a length to support an additional ribbon unit. In assembling the construction, a ribbon unit with its tongue or keeper member 72 in flat position, as shown at the right hand end of Fig. 16, is first slid onto the member 104 from the slotted end thereof until it reaches the flange or stop. The second unit, in reversed position, as shown in Fig. 16, is then inserted on base member 104 and the bar pin attached to the clothing in the identical manner described above in connection with the single-ribbon pin of Figs. 12 and 13. The bridge 105 is constructed and utilized the same as bridge 101 in the single pin.

As shown in Figs. 10, 12, and 14, the forward ends of the base member are in each instance suitably rounded to prevent catching of the

members on the ribbons when the ribbon units are passed over the base, with the flanges 88 gripping the base.

Referring now to Figs. 18-21 inclusive, a further form of the invention is shown. In this construction inner plates 106 of the ribbon-holding members are provided with laterally extending slots 108 adjacent an end thereof (see Fig. 21). Base member 110 (see Fig. 20) includes a hinge pintle 112, preferably of similar construction to that previously described, and a struck-up guide 114 substantially corresponding to guide 88 or 102 of the other forms. The end of the base member opposite the hinge pintle is provided with an elongated slot 116 adapted to be subsequently closed at its outer end by an upwardly bent integral bar 118. A keeper member 120 (see Figs. 18-19) is constructed from a thin metal strip, the keeper member including base flanges 122 of a combined area substantially equal to that of slot 108 to fit therein, as shown in Fig. 18. Upstanding integral extensions 124 of the base members 122 form an eye 126 of an outer diameter to pass through slot 116 and of an inner diameter to receive the attachment pin.

In the assembly of a bar pin of this form, the ribbon holders are constructed as previously described except that elements 106 are employed as the inner plates. In the two-ribbon construction shown, a ribbon holder is slid onto the backing member from the notched end thereof in the same manner previously described in connection with the other embodiments. The second ribbon holder, with the base of a keeper member 120 received in slot 108 and positioned to have the keeper adjacent its outer end, is then similarly slipped onto the backing member until it contacts with the first installed ribbon member. Upstruck flange 118 is then bent downwardly into the plane of the backing member to prevent complete withdrawal of the second ribbon-holding member. As will be understood, the second-ribbon-holding member can be moved back and forth to an extent limited by contact of keeper member 120 with the inward end of notch 116 and with flattened flange 118. The fastening pin carried by pintle 112 (not shown) is made of a length to be received within the eye of the keeper 120 when the ribbon holder is moved to the right, and to be released when the ribbon holder is moved to the left.

As will be appreciated, this construction is adaptable to bar pins carrying one or three or more of the ribbon holders without change except for the difference in length of the backing member and the length of the slot 116.

Referring now to Fig. 24, a slight modification of the last described embodiment is shown. In this case inner plate 128 of the ribbon-holding member includes slot 130, similarly located to slot 108, but of lesser transverse dimension than the combined extent of flanges 122 of keeper 120. As a result the base of the keeper is confined between the inner and outer plates of the ribbon-holding member, the keeper being inserted during the assembly of the latter. In this case the keeper 120 will be formed on each ribbon unit and will be flattened down on all except the last unit to be passed on to the base.

Figs. 22 and 23 disclose a minor modification of the fastening pin which may be employed in any of the several embodiments, although illustrated for use in the embodiment of Figs. 18-21. The hinge pintle previously described is eliminated, and in lieu thereof a pin 132, formed of spring

wire or the like, is provided with an integral coil spring 134, terminating in an end 136 passing beneath a portion of the backing plate and extending through an opening therein to be locked in position as illustrated particularly in Fig. 23. Owing to the presence of integral spring 134, the pin tends to swing outwardly from the backing member. Hence, when the end of the pin is confined by the keeper member, an additional frictional resistance to movement of the keeper is obtained. In addition, the pin is in a superior position for attachment purposes.

In Fig. 27 there is shown a slight modification of the ribbon holder, wherein instead of a flat plate 18 of Fig. 10, e. g., being used for the inlay, this element 138 is of the same form as the outer shell, so as to more firmly grip the ribbon between the outer shell and inlay. It will be understood that this inlay 138 may be supplied with a keeper 20 of the type herein disclosed in Figs. 10, 18 and 24 or that it may have a smooth face as in Fig. 1.

Having thus described my invention in rather full detail, it will be understood that these details need not be strictly adhered to and that 25 various changes and modifications will suggest themselves to one skilled in the art, all falling within the scope of the invention as defined by the subjoined claims.

I claim:

- 30 1. A decorative article comprising a base and a preassembled decorative unit carried by said base, said unit comprising an outer plate, an inner plate overlying the rear face of said outer plate, side flanges on said outer plate and a facing material overlying the front face of said outer plate and extending over said flanges and between said plates, said flanges extending rearwardly from said outer plate in converging relationship to confine the inner plate therebetween with said facing material gripped between said flanges and the edges of said inner plate, whereby said flanges define a dovetail channel which receives said base in endwise, sliding, frictional engagement.
- 45 2. A decorative article comprising a base and a decorative unit carried by said base, said unit comprising an outer plate, an inner plate overlying the rear face of said outer plate, side flanges on said outer plate, a facing material overlying the front face of said outer plate and extending over said flanges and between said plates, said flanges extending rearwardly and inwardly from said outer plate to confine the inner plate therebetween with said facing material gripped between said flanges and the edges of said inner plate, said flanges terminating in free edges spaced a substantial distance from said inner plate, whereby said flanges define a dovetail channel which receives said base in endwise, sliding, frictional engagement, said base carrying an attachment pin and a keeper therefor.
- 50 3. A decorative article comprising an elongated base and a plurality of decorative units mounted thereon, each of said units comprising an outer plate, an inner plate overlying the inner face of said outer plate, side flanges on said outer plate and a facing material overlying the front face of said outer plate and extending over said flanges and between said plates, said flanges extending rearwardly from said outer plate in converging planes to confine the inner plate therebetween with said facing material gripped between said flanges and the edges of said inner plate, said flanges terminating in free edges
- 55
- 60
- 65
- 70
- 75

spaced a substantial distance from the inner plate, whereby said flanges define a dovetail channel which receives the base in endwise, sliding, frictional engagement.

4. A decorative article comprising an elongated base and a plurality of decorative units mounted thereon, each of said units comprising an outer plate, an inner plate overlying the inner face of said outer plate, side flanges on said outer plate and a facing material overlying the front face of said outer plate and extending over said flanges and between said plates, said flanges extending rearwardly from said outer plate in converging planes to confine the inner plate therebetween with said facing material gripped between said flanges and the edges of said inner plate, whereby said flanges define a dovetail channel which receives said base in endwise, sliding, frictional engagement, and a stop formed integrally with said base to limit the sliding engagement of said units thereon, said base carrying an attachment pin and a keeper therefor.

5. A decorative article comprising a base and a plurality of decorative units carried by said base, each of said units including an outer plate, an inner plate overlying the rear face of said outer plate, side flanges on said outer plate and a facing material overlying the front face of said outer plate and extending over said flanges and between said plates, said flanges extending rearwardly from said outer plate in converging planes to confine the inner plate therebetween with said facing material gripped between said flanges and the edges of said inner plate, whereby said flanges define a dovetail channel which receives said base in endwise, sliding, frictional engagement, said base carrying a stop at one end thereof to limit the sliding movement of said units relative to said base, and an attaching pin carried by said base, said unit most remote from said stop carrying a keeper for receiving said pin.

6. A decorative article comprising a base and a plurality of decorative units carried by said base, each of said units including an outer plate, an inner plate overlying the rear face of said outer plate, side flanges on said outer plate and a facing material overlying the front face of said outer plate and extending over said flanges and between said plates, said flanges extending rearwardly and inwardly from said outer plate in converging planes to confine the inner plate therebetween with said facing material gripped between said flanges and the edges of said inner plate, whereby said flanges define a dovetail channel which receives said base in endwise, sliding, frictional engagement, said base carrying a stop at one end thereof to limit the sliding movement of said units relative to said base, an at-

taching pin carried by said base, said unit most remote from said stop carrying a keeper for receiving said pin, and a guide member formed integrally with said base for guiding said pin into said keeper.

7. A decorative article comprising a base and a decorative unit carried by said base, said unit comprising an outer plate, an inner plate overlying the rear face of said outer plate, side flanges on said outer plate and a facing material overlying the front face of said outer plate and extending over said flanges and between said plates, said flanges extending rearwardly from said body portion in converging planes to confine the inner plate therebetween with said facing material gripped between said flanges and the edges of said inner plate, whereby said flanges define a dovetail channel which receives said base in endwise, sliding, frictional engagement, said unit carrying an upstanding keeper member, said base having an elongated slot, an attaching pin, and means adjacent an end of said slot for positioning said pin for reception within said keeper member, said base being reduced in width adjacent one end thereof to permit it to be inserted in said channel by movement at right angles to said body portion with said keeper member entering said slot.

8. A decorative unit for assembly on a base, said unit comprising an outer plate, an inner plate overlying the rear face of said outer plate, side flanges on said outer plate and a facing material overlying the front face of said outer plate and extending over said flanges and between said plates, said flanges extending rearwardly and inwardly from said outer plate in converging planes to confine the inner plate therebetween with said facing material gripped between said flanges and the edges of said inner plate, whereby said flanges define an open-ended, dovetail channel dimensioned to receive said base in endwise, sliding, frictional engagement.

9. A decorative unit for assembly on a base, said unit comprising an outer plate, an inner plate overlying the rear face of the outer plate, side flanges on said outer plate and a facing material overlying the front face of the outer plate and extending over said flanges and between said plates, said flanges extending rearwardly and inwardly from said outer plate to confine the inner plate therebetween with said facing material gripped between said flanges and the edges of said inner plate, said flanges terminating in free edges spaced a substantial distance from said inner plate, whereby said flanges define a dovetail channel dimensioned to receive said base in endwise, sliding, frictional engagement.

JOSEPH I. LEVYN.
